UNITED STATES PATENT OFFICE

HARVEY B. AUSTIN, OF WAYNE, PENNSYLVANIA, ASSIGNOR TO THE PRINGLE ELECTRICAL MANUFACTURING COMPANY, OF PHILADELPHIA, PENNSYLVANIA, A CORPORATION OF PENNSYLVANIA

SWITCH LOCK

Application filed October 26, 1928. Serial No. 315,214.

My invention relates to knife switches that may be subjected to abnormally heavy currents with the stresses tending to burst open the switches that are incident to such currents.

A purpose of my invention is to provide novel and inexpensive means for adapting a closed switch blade to stay closed if subjected to the heavy opening stresses incident to any abnormally high current through the switch, means that will not prevent the easy opening and closure of the switch by an operator and that will be operated automatically by such opening and closure.

A further purpose is to make the initial outward pull upon the pull-ring of a switch blade operate a release for oppositely directed lateral locks that when not released are adapted to hold the switch closed against the opening stresses that are incident to any abnormally high current through the switch.

A further purpose is to start the opening movement of a switch blade by the aid of a movable member that is first used to release a lock holding the blade shut.

A further purpose is to make the opening movement of a switch blade laterally retract a lock that has been first released by the opening pull on a pull-ring of the blade.

A further purpose is to definitely lock a switch lock in its receiving position by means of the outward movement of the switch blade and of a cooperating member following the blade, the follower member moving to a position across the lock.

A further purpose is to use the closing movement of a switch blade to release a lock member operated within a stationary abutment at the side of the closing blade and to wedge the lock part way out of the abutment into a lateral recess of the blade when the blade closes, using a spring-pressed wedge member back of the lock to move the lock into its locking position and to normally block it from opening movement.

A further purpose is to lock a switch blade in closed position by means of ball members, preferably of hard steel, upon opposite sides of the blade and each extending part way into the blade and part way into a stationary

structure at the side of the outer end of the closed blade.

A further purpose is to provide the outer end of a switch blade with hard recess bearings for lock members that enter the blade from stationary side abutments when the blade closes. I may form these bearings as the recessed ends of a hard pin set transversely through the thickness of the blade end or may provide the blade with a hard metal extension beyond the jaw contacts of the switch, recessing the extension member upon opposite sides to provide the bearings.

A further purpose is to lock a switch blade in closed position by means of ball members upon opposite sides of the end of the blade, each when in locking position extending part way into the blade and part way into stationary structure along side of the blade and each having a diameter greater than the thickness of the blade and greater than the distance between the opposing faces of the structure housing the ball members.

A further purpose is to relieve the locking portion of a switch blade from the effect of hammer blows incident to repeated closures of the switch.

A further purpose is to provide an inexpensive and desirable form of pull ring that is mounted upon the end of a switch blade and that is adapted to operate a switch lock release when pulled to open the switch blade.

Further purposes will appear in the specification and in the claims.

I have elected to show two only of the different forms of my invention, showing however minor modifications, and selecting forms that are practical and efficient in operation and which well illustrate the principles involved.

Figure 1 is a side elevation of switch structure embodying one of the desirable forms of my invention, the switch blade being shown full line in closed position and in dot-and-dash line in raised position, and a dot-and-dash indication being given that the switch may be double-throw if desired.

Figure 2 is a top plan view of structure shown in Figure 1.

Figure 3 is a section taken upon the line 3—3 of Figure 1.

Figure 4 is a view corresponding to Figures 3 but showing the parts in somewhat 5 different positions, those which they occupy when the pull ring is deflected preparatory to opening the switch.

Figure 5 is a view corresponding to Figures 3 and 4 but with the parts in different 10 positions, those which they occupy when the switch has been finally opened.

Figure 6 is a fragmentary side elevation 15 of structure similar except with respect to minor details to the structure shown in Figure 3, the view corresponding except for the minor differences of structure to a section taken upon the line 6—6 of Figure 3.

Figure 7 is a fragmentary section of the blade shown in Figure 6 taken upon the line 20 7—7 to enlarged scale.

Figure 8 is a fragmentary top plan view showing a somewhat different and very desirable form of blade and lock, with the blade in closed position.

25 Figure 9 is a section taken upon the line 9—9 of Figure 8.

Figure 10 is an end view of structure shown in Figure 9.

Like numerals refer to like parts in all 30 figures.

Describing in illustration and not in limitation and referring to the drawings:—

My invention is more particularly for use with switches for electric mains.

35 These switches may at times through accident or otherwise have to carry extremely heavy currents and my invention is directed at a safety device for preventing the automatic bursting open of a switch in the event 40 that the switch is at any time subjected to abnormally heavy current.

The illustrated switch includes a metal base plate 10 spaced insulators 11 and 12 mounted upon the base plate and terminals 45 13 and 14 mounted upon the insulators.

The terminal 13 carries the usual spaced hinge contacts 15 and 16, which are plates suitably slotted at 17 into the base plate. The switch blade 19 is hinged at 18 between 50 the hinge contacts which press flat against opposite sides of the blade.

Corresponding plates 20 and 21 mounted upon the terminal 14 are the usual spaced jaw contacts that receive the outer end of 55 the blade when the switch is closed.

The blade 19 when closed extends out beyond the receiving contacts 20 and 21 and carries a pull-ring 22 for use in opening and closing the switch.

60 The pull-ring operates beyond the end of the blade in the plane of the blade but is thicker than the blade and bifurcated at 23 to provide rearwardly extending side plates 24 that in the form illustrated in Figures 15 3 to 5 are pivoted to the blade at 25 and rear-

wardly extended to support between them a pin member 26 that includes lateral extensions 27 upon opposite sides of the blade and an intermediate body 28 between the side plates and in a perforation 29 through the 70 blade.

The laterally extending portions 27 may desirably be of less diameter than the body portion and serve to release the switch lock when the pull-ring is pulled or pushed in a 75 direction to open the switch.

The range of angular movement of the pull-ring rocker may be determined by engagements between the body portion 28 and the opposite sides of the perforation 29 so through the blade, or by engagements between the intermediate portion 22 of the ring and the extreme end of the blade.

The side plate portions 24 of the pull-ring may desirably be made initially separate 85 from the ring to which they may be suitably fastened as by pins 30.

I mount a hard metal disc 31 transversely through the blade at a position offset from the perforation 29 and longitudinally recess 90 the disc at each end.

When the blade is closed the recesses in the opposite ends of the disc 31 receive the projecting portions of lock members 32 that operate in a stationary housing structure 33. 95

Desirably the lock members 32 are hard steel balls and the disc insert 31 may also desirably be of hard steel.

The housing member 33 is mounted on the terminal plate 14 across the outer ends of 100 the contact plates 20 and 21 being fastened to the terminal plate by screws 34 through suitable lugs 35.

The housing member is slotted at 36 to receive the switch blade to a depth beyond 105 the end-recesses in the disc 31 when the blade is closed, the bottom of the slot optionally forming a stop that definitely determines the closed position of the blade.

The housing member portions 37 on opposite sides of the slot 36 are bored at 38 to receive the lock members 32, the alinement of the bore being perpendicular to the plane of the blade movement and its position that to register when the blade is closed, with the recesses in the ends of the insert member 31 carried on the outer end of the blade.

The lock members 32 are positively and variantly limited in their outward positions by pin members 39 that operate square across 120 the bore 38.

The pins 39 are slidably mounted in guiding holes 40 across the bore 38 so as to be across the outwardly presented surfaces of the lock members 32 and variantly and positively limit the outward position of the lock members according to the longitudinal positions of the pins.

Each pin 39 is cut flat on the side toward the blade for some distance from its outer 125 130

end at 41 and then tapered outwardly at 42 to full diameter, and the outer ends of the guiding bores 40 are given a contour at 43 to fit the outer noncircular portion of the 5 pin.

The pins 39 are shown with narrow stems 44 that suitably limit the downward movement of the upper ends of the pins so that these ends may not be pushed down into the 10 bore beyond the noncircular portion 43.

These stems 44 preferably engage the surface of the terminal before the pull-ring lever has come to the end of its range of travel so that the initial pull upon the pull-ring 15 starts the opening movement of the switch by prying engagement between the pins 27 and the tops of the lock release members 39.

As illustrated, springs 45 surround the 20 stems are compressed between the outwardly directed surface of the terminal member 14 and the inner ends of the pins 39 so that the pins are resiliently pressed outwardly by the springs.

25 The flat portions 41 of the pins are in positions to engage the lock members 32 to limit the outward positions of the lock members.

When the pins 39 are depressed their flats 41 extend across the outsides of the respective 30 balls 32 which are then free to occupy a position far enough outwardly to permit passage of the knife blade between the opposing balls.

If the pin members 39 are in their upper 35 positions the full diameter sections of the rods are presented to the outer sides of the lock members 32, and the lock members must occupy positions in which they extend inwardly into the path of the switch blade.

40 If the switch blade be already closed during the upward movement of the pins 39, the lock members are pressed by the wedge surfaces 42 into the respective recessed ends of the insert member 31 and lock the blade 45 with respect to the casing member, in that the balls or other lock members are positively held by the pins from moving outwardly.

The switch blade cannot open unless the lock members 32 are free to be displaced outwardly from the recesses in the ends of the 50 inset member 31, and therefore cannot open unless the pins 39 are suitably depressed.

When the blade is opening it pushes back the lock members, separating the lock members 55 by the thickness of the blade, and I provide a blade follower member 46 that resiliently follows the blade until left in a position between the lock members 32.

When the switch blade is closing its inner 60 edge engages the member 46, which is then blocking the lock members apart, and pushes the member inwardly out of the way, the member 46 resiliently pressing against the inner edge of the switch blade as long as the 65 blade is closed.

When the blade is opening the member 46 follows the blade outwardly until it replaces the blade in blocking the members 32 apart in their receiving positions.

The follower member 46 is slidably mounted in a bore 47 and counterbore 48 in the intermediate portion 49 of the housing structure and part way through the terminal plate 14.

The head 50 of the follower member fits 75 the counterbore and limits the outward position of the member and a spring 51 outwardly presses the member toward its outer position, that in which its upper end blocks the lock members apart.

The thickness of the body of the follower member is preferably substantially the same as that of the blade.

When the lateral rods 39 move, their inner 80 faces slide against the outer sides of the lock members.

If the lock members are in their outer positions the lateral pin members must be in their depressed positions and if the lock members are definitely blocked by the upper end of the follower member 46 from moving inwardly from their outer positions the lateral rods cannot move up to a position that pushes the lock members inwardly.

The housing member 33 is desirably an integral block slotted in front of the blade and having the bore that cases and guides the member 46 in the plane of the switch blade and perpendicular to its length when the blade is in closed position, and the bores that case and guide the members 39 parallel to the plane of the blade, and preferably though not necessarily perpendicular to the length of the blade.

100 In operation and starting with the switch blade open, the parts have positions shown in Figure 5, the follower member spring-pressed upwardly to a position in between the lock members and the rods 39 in depressed position presenting their flat portions to the outer sides of the lock members 32, the lock members being out in their receiving position.

105 While the switch is being closed, the forward edge of the switch at 52 engages the outer end of the follower member 46 pushes the follower member ahead of it until the blade stops against the bottom of the slot 36 and is in its closed position.

110 In this position the recesses in the ends of the disc insert 26 register with the inner sides of the lock members 32, leaving the lock members free from support against their inner sides.

115 For the lock members I select sliding or rolling members each having sloping end surfaces adapted to cooperate with and simultaneously engage the sloping surfaces of the disc 31 and the surfaces of the adjacent pin 39.

120 Because these end surfaces are obtainable

in a very suitable and cheap form in the hardened steel balls of commerce, I prefer to use these balls and because the purpose is best served by a compact structure, I prefer to use a single ball rather than a row of two or more balls between the pin 39 and the socket bearing in the blade, preferring one ball on each side of the blade that engages the blade on one side and the pin 39 on the other.

I also prefer to use a single ball rather than a plurality of balls between the blade 19 and the pin 39, because this means ball locks of larger diameter and I find it desirable to have the ball diameter too great for possibility of the ball escaping into the slot 36.

I have found that the individual hard steel balls, one upon each side of the blade and of diameter greater than the width of the slot 36, make an inexpensive and very efficient form of lock.

As soon as the recesses in the ends of the disc insert 26 register with the inner ends of the lock members 32, that is, as soon as the switch blade closes, the springs 45 underneath the rods 39 lift the rods 39 which thereby wedge the lock members into the recesses of the blade, firmly blocking them against outward movement and thus firmly locking the blade to the housing 33 which is firmly fastened to the terminal 14 by the screws 34.

As a result while any abnormally high current through the switch will tend to burst the switch open, such opening is prevented by the positive locking at the members 32.

To open the switch a suitable hook is inserted in the ring 30 and the ring is pulled outwardly which causes it initially to rock upon its pivot 25 causing the pin extensions 27 that register with the tops of the pins 39, to depress the pins 39 into a position at which their flat portions 41 are opposite the lock members, leaving the lock members free to move outwardly.

Continued pull on the ring 30 may desirably initially start the opening movement by prying engagement between the outer ends of the pins 39 and the pin extensions 27 and then moves the blade out from between the contact members 20, the outward movement of the blade forcing the lock members outwardly into the recess 38.

As the switch blade is moving outwardly the follower member 46 follows it to a position between the lock members thus blocking the lock members apart in their receiving position, the lock members in turn locking the pins 39 from moving upwardly in view of the lack of room to permit the lock members to move inwardly.

During the next closure when the lock members are released by the registry of the recesses in the blade with the inner sides of the lock members, the spring pressure upon the pins 39 moves the pins upwardly to wedge

the lock members into their locking position and definitely locks them in this position.

The material of the switch blade is normally copper which is itself too soft a metal for the recess bearings that receive the lock members 32.

The seats or bearings in opposite sides of the blade for the lock members are preferably very hard, much harder than copper and in the figures thus far described, comprise the recessed ends of a hard metal disc 31 that is inserted through the thickness of the blade.

When the switch is closed it must be in position for an exact registry of the recesses of the blade with the lock members, and for this reason the blade closes against a definite stop.

In the structure of Figures 3 to 5 the stop that determines the position of closure comprises the upwardly directed surfaces of the casing or housing member 33 at the bottom of the slot 36 for a short distance at 53 (Figure 6) longitudinally of the blade on each side of the follower pin 46, the forward edge of the blade, at 54 (Figure 1 or Figure 6) coming against these surfaces at every closure.

It has been suggested that if the switch is to be opened and closed very frequently with very vigorous closures, the impacts between the surfaces 53 and 54 may gradually deform the engaging metal of the blade sufficiently to loosen the disc 31 and in the structure of Figure 6 I have guarded against this eventuality by providing a fiber stop 55 between the contact jaws 20 and 21. This stop receives the blade and deadens the impact of closure thereby avoiding any danger of deformation of the metal of the blade near the lock bearing member 31. Normally the fiber stop is not necessary, any deformation incident to the closure engagements between the surfaces 53 and 54 being immaterially small.

I desirably chamfer the edge of the engagement surface of the follower member 46 at 56 in order to avoid any distortion of this surface due to its repeated engagement with the switch when the switch is closing. Desirably too, the follower member may be hardened.

In Figures 1 to 5 I have illustrated the pull-ring 22 as composite with a pin portion 26 that extends through a suitable perforation 29 in the blade.

In some cases I may prefer to make the pull-ring an integral casting and have so illustrated it in Figures 8 to 10 where the ring 22' is pivoted at 25' upon the end of the blade and the operating lateral extensions 27' do not extend inwardly through the blade but are integral extensions from the single casting that forms the ring. Either the integral form or the composite form may be preferable, according to circumstance.

In Figures 3 to 5 I have shown the lock bearing member a hard metal disc held to

place in the blade by a friction fit. Obviously, I may provide an additional security against any loosening of the disc member by additionally fastening it to place in the blade as by means of a screw 57 threaded in the end of the blade so as to engage the disc in a suitable recess 58, as shown in Figure 7.

I have illustrated in Figures 8 to 9 another very desirable form that avoids any danger of blade distortion at the lock bearings incident to closure impacts by providing the end of the blade with a hard metal extension from the copper portion, the hard metal extension to the blade carrying the pull-ring and being laterally recessed to form the lock bearings.

The copper portion of the blade ends a little beyond the jaw contacts 20 and 21, and presents an outwardly directed end tongue 59 fitting into a rearwardly directed groove 60 of the hard extension member 61, which is desirably steel.

The tongued and grooved joint is suitably riveted at 62, and the member 61 is laterally recessed at 63 to provide the seats for the lock members 32.

Preferably the recess bearings 63 are hardened.

The lock members may be exactly as already described but when I use this hard metal extension, desirably hard steel, I prefer to stop the blade at closure against the bottom of the slot rather than against fiber material inserted between the jaw contacts.

I preferably rearwardly extend the stopping surfaces 53' so as to overlap and engage the end of the copper portion of the blade as well as the rearward edge of the extension piece, in order to eliminate or lessen stresses upon the joint incident to any hammer blows of unnecessarily vigorous switch closure.

In view of my invention and disclosure variations and modifications to meet individual whim or particular need will doubtless be come evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:

1. A switch blade recessed on opposite sides near its movable end, a pull ring movably mounted on the end of the blade, stationary abutments having opposing faces in positions respectively adjacent opposite sides of the blade end when the blade is closed, lock members having stationary bearing support upon opposite sides of the switch in the abutments and means operative by closure of the blade for moving the lock members partially out of their bearings laterally into the recesses in the switch blade.

2. A switch blade recessed on opposite sides near the movable end, a pull-ring movably mounted on the blade, stationary abutments having opposing faces in positions respectively adjacent opposite sides of the blade end when the blade is closed, lock members having stationary bearing support upon opposite sides of the switch in the abutments and means operative by closure of the blade for moving and locking the lock members partially out of their bearings laterally into the recesses in the switch blade. 70

3. A switch blade recessed on opposite sides near the movable end, a pull-ring movably mounted on the blade, stationary abutments having opposing faces in positions respectively adjacent opposite sides of the blade end when the blade is closed, hard balls having stationary bearing support upon opposite sides of the switch in the abutments and means operative by closure of the blade for moving and locking the balls partially out of their bearings laterally into the recesses in the switch blade. 75

4. In a switch, a blade having recesses upon opposite sides of its movable end, stationary laterally extending bearings in positions to register respectively with the recesses, lock members in the bearings adapted to partially enter the recesses when the switch is closed, mechanism for locking the lock members from moving out of the recesses and a release for the mechanism operated by the operation of the pull-ring when pulled to open the switch. 90

5. In a switch lock for a switch blade, a lock adapted to fasten the blade shut when the switch blade is closed and a pull-ring pivotally mounted upon the end of the blade for opening and closing the switch, a release member mounted off the blade and having an inner and an outer position and adapted to release the lock when moved from its outer to its inner position, means limiting the inward movement of the release member adapting it to support an opening pry of the pull ring upon the blade, and connections between the release member and the pull-ring adapting the pull-ring when pulled in a direction to open the switch to first release the lock and then to exert an opening pry upon the blade by reason of its engagement with the release member. 105

6. In a switch lock, a switch blade, a laterally directed stationary lock-bearing in position adjacent a side of the movable end of the blade when the blade is in closed position, a lock in the bearing adapted to laterally engage and hold the blade when the blade is in closed position and to open when the switch opens, in combination with a blade follower member movable in the plane of the blade, resiliently engaging the blade when the blade is in closed position and following the blade outwardly when the blade is opening to a 130

position at which it blocks the switch lock open.

7. In a switch, a switch lock open when the switch is open and spring-pressing toward closure, and a movable member fastening the lock open when the switch is open, adapted to be engaged and retracted by the inner edge of the closing blade to permit the lock to close when the switch is closed.

10 8. In a lock for a switch blade having a lateral recess near one end of the blade, a stationary housing member having a slot adapted to receive the movable end of the blade at the recess when the blade closes, a lock bearing in the housing registering with the lateral recess in the blade when the blade is in closed position, a lock in the bearing adapted to enter the recess to lock the blade with respect to the housing, a lock operating member having bearing in the housing parallel to the plane of the blade and perpendicular to the bearing of the lock and having wedge engagement with the outer side of the lock adapting the operating member to limit 25 the outward position of the lock according to the longitudinal position of the operating member, a spring pressing the operating member in a direction to close the lock and a blade follower member adapted to move in 30 the plane of the blade and spring-pressed to a position in which it blocks the locking operation of the lock and adapted to be engaged and retracted by the closing blade.

9. In a lock for a movable switch blade, a 35 housing at the movable end of the blade presenting a slot to receive the blade and bored transversely to the slot at right angles to the plane of the blade, bored parallel to the slot across the transverse borings, and bored 40 in the plane of the blade at the bottom of the slot in alignment across the first boring in combination with a lock in the first boring, lock operating members in the second borings and a member for holding the lock members in retracted position when the switch 45 is open in the third boring.

10. In a switch, hinge contacts, jaw contacts, a blade pivoted at the hinged contacts and adapted to be received by the jaw contacts, lateral locks respectively upon opposite sides of the blade beyond the jaw contacts, an inset bearing for the locks mounted in the extended blade and adapted to receive the locks when the blade is closed and a stop between the jaws for registering the blade in its closure position by engagement with the inner edge of the closing blade.

11. In a switch, hinge contacts, jaw contacts, a blade pivoted at the hinged contacts and adapted to be received between the jaw contacts, a hard metal extension to the blade beyond the jaw contacts having recesses upon opposite sides, lateral locks adapted to enter the recesses when the blade is in closed 60 position and a stop for receiving the blade at

closure to register the recesses with the locks.

12. In a switch, hinged contacts, jaw contacts, a blade pivoted at the hinged contacts and adapted to be received between the jaw contacts, a hard metal extension to the blade 70 beyond the jaw contacts having recesses upon opposite sides, lateral locks adapted to enter the recesses when the blade is in closed position and a stop for receiving the blade at closure to register the recesses with the locks, the stop overlapping the outer portion 75 of the blade and the adjoining inner portion of its extension.
